UNITED STATES PATENT OFFICE

ROLLAND G. WILLIAMS, OF BRANFORD, CONNECTICUT, ASSIGNOR TO MALLEABLE IRON FITTINGS COMPANY, OF BRANFORD, CONNECTICUT, A CORPORATION OF CONNECTICUT

HIGHWAY-GUARD-FENCE FIXTURE

Application filed May 18, 1929. Serial No. 364,074.

This invention relates to highway guard fence fixtures, and has for its object to simultaneously clamp the fixture to a post and to clamp the cable constituting one of the 5 strands of the fence, and to take up the slack in the cable.

The accompanying drawings illustrate this invention in its preferred form, and in these drawings

10 Figure 1 is an elevation of the structure as it appears when viewed from the road—

Figure 2 is a plan view—

Figure 3 is a section at the line 3—3 of Figure 2, the cable and securing bolt being 15 shown in elevation—

Figure 4 is a section at the line 4—4 of Figure 1 with the post omitted—

Figure 5 is a detail inside view of the outer 20 clamping member, and

Figure 6 is a section at the line 6—6 of Figure 5.

Similar numerals of reference denote like 25 parts in the several figures of the drawing.

It will be understood that the posts will be spaced apart a suitable distance and will carry two, three or more of these fixtures with cables clamped thereto, this being the usual manner in which highway guard fences are constructed, but it is not deemed necessary to show in the drawing more than one unit of the fence comprising a single post, fixture and cable.

1 is the post which is preferably fixed to the ground within a cement foundation and 35 is made of iron or steel having a shape in cross section like that of a railroad rail, with a comparatively wide flange or face 2 which fronts the roadway, a comparatively narrow face 3, and a connecting web 4.

40 5 are vise sections having at their rear outer extremities hooks 6 adapted to embrace the outer side edges of the face 2 so as to confine said edges between the hooks and seats 45 7 formed integral with the sections 5, and 8 is a screw bolt passed through said sections, with a nut 9 driven on the free end of the bolt whereby said sections may be forced toward each other so as to cause the hooks 6 to firmly embrace the part 2 whereby the vise 50 sections may be fixed to the post.

10 denotes a cable, and 11 a clamping stirrup which is somewhat elongated and has its inner face concave so as to embrace the cable, the outer faces of the vise sections being 55 formed into elongated portions 12 which are likewise concave in order to embrace the cable.

The stirrup 11 terminates at its edges in lips 13 that are engaged with ledges 14 on opposite sides of the vise sections 5, and these lips are inclined so as to gradually increase in thickness from the outer ends to a central point so that it will be clear that when the vise sections are drawn together, the action of 60 said ledges against these inclined lips will 65 cause the stirrup 11 to be drawn against the cable.

The concave surfaces of the stirrup are inclined from the ends of the latter inwardly toward a central point, these inclines being 70 denoted by the numeral 15, and the concave faces of the parts 12 of the vise sections are similarly inclined as shown at 16, and therefore it will be understood that the inclines of 75 the stirrup are respectively parallel with the inclines of the parts 12.

Therefore when the screw bolt 8 is operated to draw the vise sections together, the stirrup will be forced against the cable and the latter will be bent by the contacting inclines, as shown particularly at Figure 3, and as this bending takes place in every fixture on adjacent and successive posts, the slackness in the cables, which cannot be obviated by the usual stretching, will be fully taken up and the cables will be uniformly taut, and at the same time will be securely clamped to each fixture.

What is claimed is:—

1. The herein-described highway guard fence fixture, comprising a post, vise members including a screw bolt for securing the members to the post, a cable and a stirrup having inclined parts that are slidably supported 90 from said members, said stirrup and members having complementary parts with inclined faces that embrace the cable, whereby 95 when said bolt is tightened said members and stirrup will be clamped against the cable in inclined planes.

2. The herein-described highway guard fence fixture, comprising a post, vise members having ledges on opposite sides, a screw bolt for securing said members to the post, 5 a cable, and a stirrup having its inner ends terminating in lips that gradually increase in thickness from the outer ends to a central point, said lips supported from said ledges, said members and stirrup having elongated 10 complementary clamping parts with concave faces that embrace said cable, said faces being inclined inwardly from the ends toward the center.

15 In testimony whereof I affix my signature
hereto.

ROLLAND G. WILLIAMS.
